(57) CLAIM

The ornamental design for a wheeled pedestal for holding hair styling tools, as shown and described.

DESCRIPTION

FIG. 1 is an environmental perspective view of a wheeled pedestal for holding hair styling tools showing my new design;

FIG. 2 is a perspective view of a wheeled pedestal for holding hair styling tools;

FIG. 3 is a top plan view thereof;

FIG. 4 is a front view thereof;

FIG. 5 is a left side view thereof;

FIG. 6 is a right side thereof;

FIG. 7 is a rear view thereof; and,

FIG. 8 is a bottom plan view thereof.

The broken lines showing the hair styling tools and the work tray in FIG. 1 are for illustrative purposes only and form no part of the claimed design.
